INVENTOR,

Harold G. Fitz Gerald

UNITED STATES PATENT OFFICE.

HAROLD G. FITZ GERALD, OF LOS ANGELES, CALIFORNIA.

DESIGN FOR A REFLECTOR.

55,457.

Specification for Design. Patented June 15, 1920.

Application filed November 19, 1917. Serial No. 202,881. Term of patent 14 years.

To all whom it may concern:

Be it known that I, HAROLD G. FITZ GERALD, a citizen of the United States, residing at Los Angeles, in the county of Los Angeles and State of California, have invented a new, original, and ornamental Design for Reflectors, of which the following is a specification, reference being had to the accompanying drawing, forming part hereof.

In the drawing, Figure 1 is an edge view,

and Fig. 2 is a face view, of a reflector, each one showing my new design.

I claim:

The ornamental design for a reflector, as shown.

HAROLD G. FITZ GERALD.
